UNITED STATES PATENT OFFICE.

WILLIAM L. BARRON, OF OKLAHOMA CITY, OKLAHOMA.

VAPOR-GENERATING ATTACHMENT FOR INTERNAL-COMBUSTION ENGINES.

Application filed February 23, 1922. Serial No. 538,808.

To all whom it may concern:

Be it known that I, WILLIAM L. BARRON, a citizen of the United States, residing at Oklahoma City, in the county of Oklahoma and State of Oklahoma, have invented certain new and useful Improvements in Vapor-Generating Attachments for Internal-Combustion Engines, of which the following is a specification.

10 The present invention relates to a device for supplying moisture to an internal combustion engine and has for its object to provide a device of this character which embodies novel features of construction 15 whereby the explosive mixture will be automatically humidified before it enters the engine cylinders, thereby causing the engine to run smoothly with a maximum degree of power and assisting in eliminating 20 carbon deposits.

Further objects of the invention are to provide a charge humidifying device for internal combustion engines which is comparatively simple and inexpensive in its 25 construction, which can be readily mounted upon any conventional type of engine, which acts automatically to supply the moisture to the engine when the engine is running, and which can be readily assembled 30 or taken apart for the purpose of making repairs or adjustments.

With the above and other objects in view the invention consists in certain combinations and arrangements of the parts, as will 35 more fully appear as the description proceeds, the novel features thereof being pointed out in the appended claims.

One preferred embodiment of the invention is illustrated by the accompanying 40 drawings, in which:

Figure 1 is a side elevation of a mixture humidifying attachment which is constructed in accordance with the invention, showing the same as mounted upon an internal combustion engine.

Figure 2 is an enlarged sectional view through the vapor generating portion of the attachment.

Figure 3 is a side elevation of the vapor generator with portions broken away and shown in section.

Corresponding and like parts are referred to in the following description and indicated on all of the views of the drawing by like reference characters.

For the purpose of illustration the in-

vention is shown as applied to a conventional type of internal combustion engine A which is provided with the usual intake manifold B and exhaust manifold C. The intake manifold is intended to be connected with a carburetor and to receive the explosive mixture from the carburetor in the customary and well known manner.

The vapor generator includes a hollow casing E which encloses a float valve chamber 1. The casing is formed in complementary lower and upper sections 2 and 3, respectively, which have a detachable connection with each other. The lower section 2 is intended to receive a predetermined amount of water 4, and is formed at its base with a plug 5 which is screwed or otherwise anchored in an opening which is drilled in the exhaust manifold C at a convenient place. The plug provides a support for the casing and also serves to conduct heat from the exhaust manifold to the bottom of the casing for the purpose of vaporizing the water 4.

The water within the float chamber is maintained at a certain level by means of a needle valve 6 which is controlled by the float 7. The cover or upper section 3 of the casing is formed with a horizontally disposed water inlet 8 which receives the end of a water supply pipe 9, said pipe being suitably connected with the water cooling system of the engine. In the present instance the end of the water supply pipe is fitted within an opening which is drilled in the water jacket of the engine, and the level of the water in the cooling system of the engine is sufficiently high to provide for a flow of water through the pipe 9 and into the interior of the casing E whenever the needle valve 6 is opened. The needle valve is vertically disposed and engages a valve seat which is suitably arranged in a duct 10 extending downwardly from the inner end of the water inlet 8. The needle valve is directed in its up and down movements by the walls of the duct and has the sides thereof provided with longitudinally extending recesses or cut-away portions 6a so that the water can flow freely around the sides thereof. The lower end of the needle valve engages a pivoted arm 11 which carries the float valve 7. This arm is pivoted upon a pin 12 connecting ears 13 which are provided upon the lower portion of the upper casing section 3. It will thus be ob-

vious that the float, needle valve and water pipe connection are mounted upon and carried by the top 3 of the casing so that they are removable with the top and can be readily adjusted or repaired when the top is lifted away from the base 2.

An enlargement 14 is provided at the upper portion of the casing top 3 and has a horizontally disposed valve chamber therein. 10 The outer end of the valve chamber receives one end of a vapor pipe 16 which leads to the intake manifold. In the present instance the other end of the vapor pipe enters the base of the intake manifold through an opening provided in one side thereof, a nut 17 being utilized to obtain a tight and rigid connection. The inner end of the valve chamber 15 communicates through the intersecting passages 18 and 19 with the interior 15 of the casing E. An outwardly opening valve 20 is arranged within the valve chamber 15 and is normally held in a yielding engagement with the valve seat 21 which is provided at the intersection of the passage 18 20 and the valve chamber 15. The valve 20 is slidably mounted upon a horizontally disposed stem 22 which extends axially through the passage 18 and the valve chamber 15. A coil spring 23 which surrounds the valve 25 stem is interposed between the valve and an abutment 24 on the inner end thereof. The valve is thus held in a normal engagement with the valve seat 21, although it is adapted to be automatically opened by the suction 30 of the engine to permit the vapor and air within the casing E to be drawn through the vapor supply pipe 16 into the intake manifold B.

The free end of the valve stem 22 projects through one side of the casing where it is threaded and provided with a pair of nuts 25. One of these nuts acts as a jam nut to lock the other nut against rotation, thereby enabling the device to retain an adjustment. It will be obvious that by properly manipulating these nuts 25 the valve stem 22 can be moved in and out and the tension in the spring 23 regulated so that more or less of the moisture can be permitted to 45 pass the automatic valve. The device can thus be properly adjusted to obtain the best results in connection with different makes and types of engines and for use under various conditions of service.

50 The top of the casing is also shown as provided with small air inlet openings 26. When the engine is in operation the heat from the exhaust manifold will vaporize the water 4 in the bottom of the casing E and cause the upper portion of the casing to be filled with a mixture of air and water vapor. The 55 partial vacuum which is maintained in the intake manifold B of the engine while the engine is running will be transmitted through the vapor supply pipe 16 to the valve chamber

60 14, with the result that the valve 20 will be opened and a mixture of air and vapor drawn into the intake manifold through the pipe 16. Air enters the casing E freely through the ports or openings 26, and as this air is drawn into the intake manifold it carries the vapor or steam from the water 4 along with it. The action of the float valve maintains the water 4 within the casing E at a constant level and the device is entirely 65 automatic in its operation. After the nuts 25 have been once adjusted the valve 20 will automatically supply the proper quantity of humidity and air to the intake manifold while the engine is in operation. The spring 70 23 will, of course, automatically close the valve and maintain it in a closed position when the engine is not running. All of the valve parts and pipe connections are on the top or cover 3 of the casing so that they can be readily assembled thereon before the cover is applied to the part 2. This also facilitates any necessary adjustment or repair of the parts when the cover portion 3 of the casing 75 is removed. The sections 2 and 3 of the casing have a complementary formation and cooperate with each other to provide a closed chamber. The top 3 is shown as provided at its lower edge with a peripheral flange 26 which telescopes within the upper end of the casing section 2, the over-lapping portions at the meeting edges of the two casing sections being fastened together with suitable members such as the screws 27. When the screws are removed the casing sections 80 can be separated and all of the parts of the mechanism will then be readily accessible. The device can be readily mounted upon the engine and the humidity which is supplied thereby to the explosive mixture assists in eliminating carbon deposits, and also causes the engine to run more efficiently.

Having thus described my invention, what I claim as new and desire to secure by Letters Patent is:

1. The combination with an internal combustion engine having exhaust and intake manifolds, of a vapor generator comprising a water chamber having a separate valve 115 chamber directly communicating with the upper portion of the water chamber, a water inlet and automatic valve control means therefor, a vapor pipe leading from the valve chamber to the intake manifold, and an automatically seated valve in said chamber disposed to be opened by suction from the intake manifold and to maintain pressure in the generator when closed.

2. A humidifying device for an internal 125 combustion engine comprising a water receptacle adapted for attachment to said engine, a detachable cover for the water receptacle provided with a vapor chamber, a discharge valve chamber having an auto- 130

matically closed valve, and a valved water intake, a water inlet pipe communicating with said cover, and a float valve mechanism mounted upon the cover to control said intake valve, and a vapor pipe leading from the discharge valve chamber to the engine.

3. A humidifying device for an internal combustion engine comprising a water receptacle adapted for attachment to said engine, a detachable cover closing the water receptacle and provided with a valve chamber and a passage connecting the valve chamber to the inner face of the cover, a stem extending through the valve chamber, an outwardly opening check valve mounted upon the stem, means exterior of the valve chamber for adjusting the stem to regulate the action of the valve, and a vapor pipe leading from the valve chamber to the engine.

4. A humidifying device for an internal combustion engine comprising a water receptacle adapted for attachment to said engine, a detachable cover closing the water receptacle, a water inlet pipe attached to the cover, valve means mounted upon and

carried by the cover and automatically regulating the flow of water into the receptacle, a vapor pipe leading from the cover to the engine, and valve means mounted upon and carried by the cover for automatically controlling communication between the receptacle and the vapor pipe.

5. A humidifying device for an internal combustion engine comprising a closed casing mounted thereon and adapted to receive water to be vaporized, the walls of the casing being formed with a valve chamber and a passage leading to the valve chamber, a stem having one end thereof projecting into the valve chamber while the other end projects from the exterior of the casing, a check valve slidably mounted upon the stem, a spring carried by the stem and engaging the check valve, means at the exterior of the casing for adjusting the stem to regulate the tension of the spring, and a vapor pipe leading from the valve chamber to the engine.

In testimony whereof I affix my signature.

WILLIAM L. BARRON.
